UNITED STATES PATENT OFFICE

160,563

AIRPLANE

Armand J. Thieblot, Hagerstown, Md., assignor to
Fairchild Engine and Airplane Corporation, a
corporation of Maryland

Application February 10, 1950, Serial No. 7,883

Term of patent 14 years

(Cl. D71—1)

To all whom it may concern:

Be it known that I, Armand J. Thieblot, a citizen of the United States of America, residing in the city of Hagerstown, in the county of Washington and State of Maryland, have invented a new, original, and ornamental Design for an Airplane, of which the following is a specification, reference being had to the accompanying drawings, forming a part hereof.

Fig. 1 is a side perspective view of an airplane from above, showing the new design;

Fig. 2 is a side perspective view taken from below;

Fig. 3 is a side elevational view; and

Fig. 4 is a rear elevational view thereof.

The characteristic features of the design reside in the portion shown in full lines in the drawings.

I claim:

The ornamental design for an airplane, substantially as shown and described.

ARMAND J. THIEBLOT.
